UNITED STATES PATENT OFFICE

162,588

CAR WASHING GUN OR SIMILAR ARTICLE

Leo G. Simms, Glendale, Calif., assignor to Win-kitty Products, Inc., Kansas City, Mo., a corporation of Missouri

Application May 24, 1949, Serial No. 3,839

Term of patent 14 years

(Cl. D62—2)

To all whom it may concern:

Be it known that I, Leo G. Simms, a citizen of the United States, residing at Glendale, county of Los Angeles, State of California, have invented a new, original, and ornamental Design for a Car Washing Gun or Similar Article, of which the following is a specification, reference being had to the accompanying drawing, forming a part thereof, and in which:

Fig. 1 is a top plan view of a car washing gun, showing my new design,

Fig. 2 is a side elevation of the gun when positioned as shown in Fig. 1,

Fig. 3 is a bottom plan view of the gun, and

Figs. 4 and 5 are left and right hand end elevations, respectively, of the gun when positioned as shown in Fig. 2.

I claim:

The ornamental design for a car washing gun or similar article, substantially as shown.

LEO G. SIMMS.
